(57) **CLAIM**

I claim the ornamental design for a utility vehicle front body panel, as shown and described.

DESCRIPTION

FIG. 1 is a perspective view of a first embodiment of the utility vehicle front body panel of the present invention; FIG. 2 is a front elevational view of the utility vehicle front body panel of FIG. 1;

FIG. 3 is a top plan view of the utility vehicle front body panel of FIG. 1;

FIG. 4 is a left side elevational view of the utility vehicle front body panel of FIG. 1, the right side view being a mirror image thereof;

FIG. 5 is a rear elevational view of the utility vehicle front body panel of FIG. 1;

FIG. 6 is a bottom plan view of the utility vehicle front body panel of FIG. 1;

FIG. 7 is a perspective view of a second embodiment of the utility vehicle front body panel of the present invention;

FIG. 8 is a front elevational view of the utility vehicle front body panel of FIG. 7;

FIG. 9 is a top plan view of the utility vehicle front body panel of FIG. 7;

FIG. 10 is a left side elevational view of the utility vehicle front body panel of FIG. 7, the right side view being a mirror image thereof;

FIG. 11 is a rear elevational view of the utility vehicle front body panel of FIG. 7; and,

FIG. 12 is a bottom plan view of the utility vehicle front body panel of FIG. 7.
